SASH LIFT

Fritz C. Benson, West Haven, Conn., assignor to The
H. B. Ives Company, New Haven, Conn., a corporation
of Connecticut

Application February 25, 1954, Serial No. 29,202

Term of patent 14 years

(Cl. D10—10)

Fig. 1.

Fig. 2.

Fig. 3.

To all whom it may concern:

Be it known that I, Fritz C. Benson, a citizen of the United States, residing in West Haven, in the county of New Haven and State of Connecticut, have invented a new, original, and ornamental Design for a Sash Lift, of which the following is a specification, reference being had to the accompanying drawing, forming part thereof, in which:

Fig. 1 is a top plan view of a sash lift embodying my new design;

Fig. 2 is a front elevational view thereof; and

Fig. 3 is an end elevational view.

I claim:

The ornamental design for a sash lift, substantially as shown.
